SWITCH

Application filed May 22, 1931. Serial No. 539,211.

This invention relates to electrical switches for automobiles and particularly to switches which are adapted to be mounted adjacent the lower end of a steering column of an automobile and to be operated by a shaft extending through the column and operated from upper end thereof.

An object of the present invention resides in the provision of a switch unit which is simple in its construction, inexpensive to manufacture, easy to apply, easy to manipulate, and efficient and dependable in use and operation.

Further objects and advantages of the present invention will be apparent from the following description, reference being had to the accompanying drawing wherein a preferred embodiment of one form of the present invention is clearly shown.

20 In the drawing:

Fig. 1 is a sectional view of the present invention taken substantially on the line 1—1 of Fig. 2.

Figs. 2, 3 and 4 are sectional views taken on the lines 2—2, 3—3, and 4—4, respectively of Fig. 1.

Referring to the drawing, 20 designates a switch housing or casing preferably of cup-shaped formation in which the switch mechanisms are mounted. A mounting bracket 21 is secured to the housing 20 in any suitable manner such as spot welding or otherwise and adapted to be bolted or otherwise secured to the lower end of an automotive vehicle steering column, not shown. The bracket 21 has a central aperture 22 through which the lower end of an actuating rod 23 extends, the rod being rotatably mounted in the steering column and having suitable lever or other actuating means, not shown, at its upper end.

The switch housing 20 of cup-shaped formation has a cylindrical wall 25 and a flat end wall 26. The open end of the housing is closed by a terminal back 27 secured in place by tongues on projections 28 extended from the peripheral edge of the wall 25 to engage notches provided in the terminal back 27 and the tongues are bent over in the manner as illustrated in Fig. 1. The back is preferably formed of insulating material and has on

its inner face a plurality of rivets the heads of which provide stationary contacts 29 arranged in a circular row.

It will be seen that the contacts 29 are raised from the inner face of the terminal 55 back 27. To obtain a flush surface there is attached to the back 27 an insulating ring or lining 30 having a central aperture 31 and a plurality of openings 32 registering respectively with the contacts 29 so that the 60 inner face of the ring will be flush with the faces of the contacts 29, as seen in Fig. 1, allowing the movable contacts, to be later described, to ride freely upon or off the contacts 29.

Within the housing is a dielectric contact support or carrier 35 having arms or lugs 36, 37 and 38 each notched at 39. The support 35 has a central opening 40 provided with key or lugs 41 that fit into notches 42 70 of a tubular driving shaft 43 to provide a driving connection therewith, while allowing the support 35 to move axially thereof. The support 35 is provided with a plurality of recesses 44 adjacent the wall 26. The wall 75 26 has a plurality of bosses or projections 45 struck therefrom and arranged in a circular row to register with certain of the recesses 44 in the support 35 and provide the necessary detent or ratchet action when the projections 45 ride into and out of the recesses 44.

Mounted on the dielectric support 35 adjacent the stationary contacts 29 is a triangular shaped member 50 having tongues 51, 55 extending through notches 39 provided in the arms 36, 37 and 38 and bent over at 53. The member 50 is free to move axially on the support 35, but is held against rotation with respect to the support due to the tongues 51 90 engaging the notches 39. Interposed between the member 50 and the dielectric support 35 are a plurality of coiled springs 52, as indicated in Fig. 3. The springs are seated in recesses 54 provided in the support 35 95 and urge yieldingly the contact bosses 59 against the back 27, and also urge the recesses 44 over the projections 45 on the wall 27 to retain yieldingly the contacts 59 and the support 35 in a desired position. The 100

3. springs 52 also prevent the member 50 from rocking when said member is moved from one position to another. The recesses 44 and projections 45 are so located with respect to each other and the contact 29, that for each position of the switch contact assembly, the three projections 45 which are shown in dotted lines in Fig. 3, will be received by three of the recesses 44. In this way the movable contact plate 50 is retained yielding in different positions.

15 The end wall 27 is provided with a partially sheared portion 60 bent inwardly and interposed in the circular path of movement of the arms 36 and 37. Thus the portion 60 acts as a stop to limit the rotation of the support 35.

20 The switch back 27 is provided with an aperture 61 to provide a bearing surface for a reduced portion 62 of the tubular driving shaft 43 that extends exteriorly of the switch housing, as shown in Fig. 1. The actuating shaft 23 passes through the elements of the switch structure and is secured to the driving shaft 43 by the tightening of a nut 64 which wedges against the shaft 23 a plurality of threaded fingers 63 integral with the shaft 43 and separated from each other by longitudinal slots 65.

25 30 While the form of embodiment of the present invention as herein disclosed, constitutes a preferred form, it is to be understood that other forms might be adopted, all coming within the scope of the claims which follow.

35 What is claimed is as follows:

1. An electric switch comprising in combination; a casing having parallel walls, one of which is provided with stationary contacts and the other with a series of projections; a contact assembly including a contact carrier having recesses adjacent the projections, a contact member attached to said carrier and provided with bosses adjacent the stationary contacts, a plurality of springs in a circular row confined between the contact member and the carrier for urging the contact member against the stationary contacts and the carrier toward the casing wall having the projections and means for rotating said assembly.

2. An electric switch comprising in combination; a casing having parallel walls, one of which is provided with stationary contacts and the other with a series of projections; a contact assembly including a contact carrier having recesses adjacent the projections, a contact member attached to said carrier and provided with contact bosses adjacent the stationary contacts, and a plurality of springs interposed between the contact member and the carrier to urge them apart, said springs bearing on the contact member adjacent the contact bosses; and means for rotating said assembly.

3. An electric switch comprising in combination; a casing having parallel walls, one of which is provided with stationary contacts and the other with a series of projections; a movable carrier and a movable contact plate provided between said walls; resilient means urging the carrier and the plate apart including coiled springs located between the carrier and the plate, one end of each spring being received by one of several recesses in the carrier and the other end bearing against the plate, said plate having means for connecting said plate to the carrier, and said carrier having recesses for receiving the projections of one of said walls whereby the springs 75 80 85 90 95 100 105 110 115 120 125 130 135 140 145 150 155 160 165 170 175 180 185 190 195 200 205 210 215 220 225 230 235
